(57) CLAIM

The ornamental design for a blanket clip, as shown and described.

DESCRIPTION

FIG. 1 is a front perspective view of a blanket clip showing my new design;

FIG. 2 is a front elevational view of the blanket clip shown in FIG. 1;

FIG. 3 is a rear elevational view of the blanket clip shown in FIG. 1;

FIG. 4 is a side elevational view of the blanket clip shown in FIG. 1; and,

FIG. 5 is a top plan view of the blanket clip shown in FIG. 1.

The broken line showing of stitching in FIGS. 1-5 is for illustrative purposes only and forms no part of the claimed design.
